US00D615430S

(12) **United States Design Patent**
Wieberdink et al.

(10) **Patent No.:** US D615,430 S
(45) **Date of Patent:** ** May 11, 2010

(54) **ELECTRICAL PROBE**

(75) Inventors: **Natalie M. Wieberdink**, Cedar Grove, WI (US); **Derek D. Erickson**, Milwaukee, WI (US); **David J. Prince**, Eau Claire, WI (US); **Joseph M. Hillary**, Eden Prairie, MN (US); **Christopher L. Peterson**, Chippewa Falls, WI (US)

(73) Assignee: **Actuant Corporation**, Butler, WI (US)

(**) Term: **14 Years**

(21) Appl. No.: **29/338,113**

(22) Filed: **Jun. 4, 2009**

(51) **LOC (9) Cl.** 10-04

(52) **U.S. Cl.** D10/78

(58) **Field of Classification Search** D10/78; 324/555, 556, 114, 133, 156, 72.5, 508; 340/654; 379/21; 73/866.5

See application file for complete search history.

(57) **CLAIM**

The ornamental design for an electrical probe, as shown and described.

DESCRIPTION

FIG. 1 is a perspective view of an electrical probe showing our new design;

FIG. 2 is a top elevational view thereof;

FIG. 3 is a bottom elevational view thereof;

FIG. 4 is a left side elevational view thereof;

FIG. 5 is a right side elevational view thereof;

FIG. 6 is a rear end elevational view thereof; and,

FIG. 7 is a front end elevational view thereof.

The broken line representations of portions of the electrical probe in FIGS. 1–7 do not limit the claimed design.
